UNITED STATES PATENT OFFICE.

THEODOR SABALITSCHKA, OF BERLIN-STEGLITZ, AND HEINRICH JACOBSON,
OF BERLIN-DAHLEM, GERMANY.

DISINFECTING.

No Drawing. Application filed December 22, 1925, Serial No. 77,119, and in Germany December 24, 1924.

Our invention relates to improvements in disinfecting preparations and the process of manufacturing the same, and more particularly in preparations using an ester of hydroxybenzoic acids as a disinfecting agent. It is known in the art that the esters of the salicylic acid, the alkyl ester as well as the phenyl esters, have disinfecting properties, for which reason the said substances have been used in the manufacture of preparations for cleaning the mouth, ointments, soap preparations, and the like. However, such preparations are objectionable for the reason that the esters of the orthohydroxybenzoic acid such as the preparations known in the trade as wintergreen oil and salol have a strong odor of their own, and that they are poisonous, the salol being highly poisonous, while the wintergreen oil is poisonous in a less degree.

We have discovered that only the ester of the orthohydroxybenzoic acid is poisonous, and that non-poisonous disinfecting preparations are obtained when using the esters of the meta- or parahydroxybenzoic acids and more particularly the alkyl esters of the said compounds. These alkyl esters of the meta- and parahydroxybenzoic acid are odorless and non-poisonous. Further, what is important from a practical point of view, they are solid crystallizable substances, so that they may be incorporated with preparations such as soaps, liquids for cleaning the mouth, ointments, pastes, and the like having high disinfecting properties, and having no odor or taste of the active disinfecting medium.

Example 1.—150 grammes of an alkyl ester

of the meta- or parahydroxybenzoic acid are dissolved in 1 liter of alcohol. The preparation added to water is used for disinfecting the mouth.

Example 2.—0.05 grammes of an alkyl ester of the meta- or parahydroxybenzoic acid are added to 0.5 grammes of sugar and pressed to tablets. After being dissolved in water the preparation is used for vaginal cleansing.

Example 3.—To soap containing yolk, such as ray soap, we add 5% of an alkyl ester of the meta or parahydroxybenzoic acid.

Since in the ortho compounds the substituents are connected to adjacent carbon atoms in the benzene ring, and since in the meta- and para- compounds, the substituents are connected to non-adjacent carbon atoms, the term "non-adjacent hydroxybenzoic acid" will hereinafter be used to define the said meta- and para- compounds.

We claim:

1. The herein described improvement in the art of disinfection which comprises applying to the material to be disinfected, a substance containing an ester of a non-adjacent hydroxybenzoic acid.

2. The herein described improvement in the art of disinfection which comprises applying to the material to be disinfected, a substance containing an alkyl ester of a non-adjacent hydroxybenzoic acid.

In testimony whereof we hereunto affix our signatures.

DR. THEODOR SABALITSCHKA.
HEINRICH JACOBSON.
